UNITED STATES PATENT OFFICE

1,976,703

MECHANICAL MOVEMENT

Anthony L. Vissat, Bridgeville, Pa., assignor of
one-half to Harry L. Gleeson, Pittsburgh, Pa.

Application March 6, 1933, Serial No. 659,593

13 Claims. (Cl. 74—50)

My invention may be advantageously employed in numerous mechanical arts. For instance, it is particularly useful in the railway art for shifting switch-rails, frog-members, signals and the like, or for locking a rotary member against further movement, as in motor vehicle or railway brakes.

My invention consists in a new and improved mechanical movement whereby a member, such 10 for instance as a slidably mounted plate may be moved a predetermined distance in either direction and is automatically locked against further movement in the same direction at either end of its path, and is also automatically locked against 15 return movement except by the rotation of an actuating disk.

The slidable member is provided with an oblong opening having its longer axis disposed transversely to the path of movement of the member. A 20 circular disk is mounted within the opening and is arranged to rotate on an eccentric axis. The longer axis of the opening is at least equal to the diameter of the disk plus the distance between the axis of the disk's rotation and the true center 25 of the disk with working clearance, and the articulate ends of the opening are described on the radius of the disk with working clearance. The disk is eccentrically mounted to rotate on or around a fixed axis so located that at either end of a movement of the disk the latter seats in the same end of the opening, leaving a lune-shaped vacancy at the other end of the opening which provides clearance for the rotation of the disk to move the plate. At the completion of a movement the disk 30 is seated in the end of the opening and the member and disk are thus locked against further movement in the same direction, and the member is also locked against return movement except by the rotation of the disk.

40 Rotary movement may be applied to the disk in any suitable manner, as for instance by means of a crank, gears or rack and pinion.

It is obvious that the throw of the disk and 45 therefore the length of the path of movement of the slidable member is regulated by the eccentricity of the disk. Therefore I have invented an improved disk structure wherein the eccentricity may be varied to obtain the desired throw. If 50 desired the disk may be arranged to lock at only one end of its throw.

In the accompanying drawings wherein I have 55 illustrated a practical embodiment of the principles of my invention, Fig. 1 is a plan view showing a simplified form of my improved mechanical

movement, the slidable member being shown at the right end of its path of movement.

Fig. 2 is a similar view showing the slidable member at the opposite or left end of its path of movement.

Fig. 3 is a longitudinal section taken along the line 3—3 in Fig. 1.

Fig. 4 is a transverse section taken along the line 4—4 in Fig. 1.

Fig. 5 is a plan view showing my invention embodied in a switch operating mechanism, the slidable member being shown at the right end of its path of movement.

Fig. 6 is a similar view showing the member at the opposite or left end of its path of movement.

Fig. 7 is a like view showing the member in an intermediate position.

Fig. 8 is an end view looking from the left in Fig. 5.

Fig. 9 is a cross sectional view taken along the line 9—9 in Fig. 5.

Fig. 10 is a plan view showing my invention applied to an electrically or manually operated railway switch, the slidable member being shown at the right end of its path of movement.

Fig. 11 is a similar view showing the member at the left end of its path of movement.

Fig. 12 is a longitudinal section taken along the line 12—12 in Fig. 11.

Fig. 13 is a plan view showing another embodiment of my invention, the bearing of the crank being omitted for the sake of clearness.

Fig. 14 is a cross section taken along the line 14—14 in Fig. 13, the bearing for the crank being shown.

Fig. 15 is a plan view of another embodiment of the principles of my invention.

Fig. 16 is a sectional view of the same taken along the line 16—16 in Fig. 15.

Fig. 17 is a plan view showing a slidable member arranged to be moved by a disk whose eccentricity may be varied to obtain different throws, the pinion being omitted.

Fig. 18 is a sectional view taken along the line 18—18 in Fig. 17, the pinion being shown.

Fig. 19 is a plan view similar to Fig. 17 but showing another means for varying the eccentricity of the disk, the pinion being omitted.

Fig. 20 is a sectional view taken along the line 20—20 in Fig. 19, the pinion being shown.

Referring first to Figs. 1 to 4, inclusive, 1 represents a base having parallel side walls 2 whose inner faces are provided with the guide ribs 3 on which is slidably mounted a member or plate 4 which has rods or bars 4a extending from either

end and connected to elements to be shifted or locked by the movement of the member 4.

The plate 4 is provided with a seat, preferably in the form of an opening 5 of oblong contour 5 with its longer axis disposed transversely to the path of movement of the plate 4. 6 is a circular disk which moves in the opening 5. The disk 6 is eccentrically mounted on and fixed to a vertically disposed shaft 7 which is suitably journaled in the base 1 as by means of the step bearing 8 on said base. The upper end of the shaft is provided with a crank 9. In practice an upper bearing for the shaft is preferably provided, but the same is omitted in the drawings for the sake 10 of clearness.

The longer axis of the opening 5 is at least equal to the diameter of the disk 6 plus the distance between the axis of the disk's rotation and the true center of the disk with working clearance 20 and the shorter diameter of the opening is equal to the diameter of the disk with working clearance. The arcuate ends of said opening are described on a radius equal to the radius of the disk with working clearance. The shaft 7 is so 25 located relative to the opening that as the disk rotates and the plate moves, the axis of said shaft moves along the cord of the semi-circle which forms one end of the opening, the lower end in Figs. 1 and 2.

30 Thus as the disk is rotated counterclockwise through an arc of 180 degrees, the disk will move from its position shown in Fig. 1 to that shown in Fig. 2, thus moving the plate from right to left a distance determined by the eccentricity 35 of the disk, and in like manner when the disk is rotated clockwise from its position shown in Fig. 2 to that shown in Fig. 1, the plate will be moved a like distance from left to right.

40 As the disk completes either movement and its radius of eccentricity is disposed substantially parallel with the path of movement of the plate, the disk nests in the end of the opening in the plate and thus locks the plate against further movement in that direction. Also the plate is 45 thus locked against return movement unless the disk is rotated in the proper direction by power applied to the crank. The lune vacancy shown at 9a provides clearance for the rotation of the disk from one of its extreme and nested positions 50 to the other and vice versa.

If desired the disk may be arranged to lock in only one of its terminal positions.

55 Referring now to Figs. 5 to 9, inclusive, where in my invention is shown applied to a switch-throwing mechanism, 10 represents the parallel cross-ties upon which is mounted the box 11, spikes being driven through brackets 12 on the box into the ties. The plate 4 slides on the bottom 60 13 of the box, being held in place by means of angle bars 14 secured to the side walls of the box.

The disk 6 works in the opening 5 of the plate 4 and is fixed on the vertically disposed shaft 7 having an enlarged base 15 which is stepped in a bearing 8a in the bottom 13 of the box.

65 16 represents a bevelled pinion fixed on the upper end of the shaft 7 and to the disk 6, and in mesh with a second bevelled pinion 17 fixed on the end of a horizontal shaft 18 journaled in a bearing 19 on the cross bar 20 of the box 11 and also in a bearing in the end wall of the box. The outer end of the shaft has fixed thereto the switch lever 21. 22 represents a link which connects the plate 4 with the switch rail or other element to be moved.

70 When the plate 4 is at the right end of its path

of movement, as illustrated in Fig. 5, the switch lever 21 is in the position shown in solid lines in Fig. 8. When the plate 4 is at the opposite end of its path of movement, as illustrated in Fig. 6, the lever is in the position indicated in dotted lines at 21a in Fig. 8, and when the plate is in its central or intermediate position, as illustrated in Fig. 7, the lever is in the position shown in dotted lines at 21b in Fig. 8.

80 Referring now to Figs. 10, 11 and 12, wherein the invention is shown applied to an electrically or manually operated street-railway switch, 23 represents a box which when in use is sunk in the roadbed and is provided with a suitable lid, not shown. The plate 4 slides in the box 23 being held in place by the guide bars 24. The pinion 25 is bolted to the disk 6 and both revolve on the post 26 which rises from the box, a nut 27 maintaining the disk and pinion in place to rotate on the post. Meshing with the pinion 25 is a rack bar 28 which is held in position by overhanging guide bar 29 fixed on the plate 4. The rack bar 28 extends rearwardly through an opening in the partition 30 of the box 23 and is provided at its outer end with a cross notch 31 having opposed arcuate walls engaged by a lever 32 pivotally supported at 33 from the floor of the box and provided at its short end with holes 34 for a switch iron or other manual or mechanical operating means. 35 represents a link or other connection to mechanical operating means, such for instance as a solenoid or motor.

90 Referring now to Figs. 13 and 14, 36 represents a plate whose seat 37 to receive the disk 6 is perimetricaly defined by a continuous ledge 38 of proper contour to function as an oblong opening for the disk 6. The ends of the plate are provided with bars 39 which work in slide bearings 40 in supports 41. 42 represents a bearing for the crank shaft 43 upon which the disk 6 is fixed.

95 In Figs. 15 and 16, I show the slidable member formed by parallel and spaced apart plates 44 which are connected in spaced relation by means of the spacer blocks 45 whose adjacent faces are provided with the opposed arcuate edge portions 100 46 which coact to form the oblong opening for the disk 6 which is mounted between the plates 44. The plates 44 are provided with longitudinal slots 47 to provide clearance for the shaft 48 on which the disk 6 is mounted. The lower end 105 of the shaft being stepped in a bearing 49. The upper end of the shaft being provided with any suitable means for rotating the disk, such as a crank or pinion.

110 It is evident that the disk, where it is pinion rotated, may be fixed on a rotary shaft or may rotate on a fixed post, as may be found desirable.

115 Antifriction bearings may be interposed between the perimetral edge of the disk and its seat, or otherwise provided to reduce friction of 120 relative rotary movement.

125 Referring now to Figs. 17 and 18, the disk is provided with a diametrically disposed slotted opening 50 having a cross bar 51 which is notched downwardly to receive the shank of a bolt 52 130 whose head is interposed between the cross bar and the adjacent end of the slot to prevent longitudinal movement of the bolt. The bolt is threaded into a hole in a block 53 slidable in the slot 50 and provided with an upwardly extending tubular neck 54 upon which is mounted the pinion 55 held in place and fixed relative to the disk and block as by means of a nut 56 screwed down on the threaded upper end of the neck. The post 57 extends up through the tu-

145

150

bular neck so that the disk and pinion assembly is thus rotatably mounted on the post and the disk rotates in the opening of the plate 4 to move the latter longitudinally.

5 Thus by rotating the bolt 52 in the proper direction the eccentricity of the disk may be regulated.

Referring now to Figs. 19 and 20, the disk 6 is provided with a diametrically disposed slotted opening 58 in which is slidably mounted the block 59 which rotates with the disk and also with the pinion 60 mounted on the block above the disk. The block is provided with a bore through which extends the post 61 upon which the disk and pinion assembly rotates, a washer and nut 62 being applied to the threaded upper end of the post. 63 represents shims or spacer plates which are used to position the block 59 in the proper position along the slotted opening 58 to give the disk the desired eccentricity. By shifting the spacer plates 63 the axis of rotation of the disk may be varied as desired.

It is obvious that where the eccentricity of the disk is adjustable, the longer axis of the seat must be at least equal to the diameter of the disk plus the maximum distance between the axis of movement of the disk and the true center of the disk.

It is obvious that any throw or length of longitudinal movement may be obtained by regulating the size of the disk and the eccentricity or throw of the disk.

The disk may be operated by any convenient means, either manually or by power application.

35 I claim:—

1. In a mechanical movement, the combination of a support, a member mounted to slide on said support and provided with a seat elongated transversely to the path of movement of the member, and a circular disk mounted for rotation on an eccentric axis in said seat, an end of the seat being provided with an arcuate portion described on a radius substantially equal to the radius of the disk and the disk being so disposed that at the end of a movement of the member the disk nests in said arcuate portion and locks the member against motion except by the reverse rotation of the disk.

2. In a mechanical movement, the combination of a support, a member mounted to slide on said support and provided with a seat elongated transversely to the path of movement of the member, a circular disk mounted for rotation on an eccentric axis in said seat, an end of the seat being provided with an arcuate portion described on a radius substantially equal to the radius of the disk and the disk being so disposed that at the end of a movement of the member the disk nests in said arcuate portion and locks the member against motion except by the reverse rotation of the disk, and means to vary the eccentricity of the disk whereby to regulate the length of the path of movement of the member.

3. In a mechanical movement, the combination of a support, a member mounted to slide on said support and provided with a seat elongated transversely to the path of movement of the member, and a circular disk mounted for rotation on an eccentric axis in said seat, an end of the seat being provided with a substantially semi-circular portion described on a radius substantially the same as that of the disk and the disk being so disposed that at the end of rotation of the disk in either direction the disk nests in said semi-circular portion and locks the member

against movement except by a reverse rotation of the disk.

4. In a mechanical movement, the combination of a support, a member mounted to slide on said support and provided with a seat elongated transversely to the path of movement of the member, a circular disk mounted for rotation on an eccentric axis in said seat, an end of the seat being provided with a substantially semi-circular portion described on a radius substantially the same as that of the disk and the disk being so disposed that at the end of rotation of the disk in either direction the disk nests in said semi-circular portion and locks the member against movement except by a reverse rotation of the disk, and means to vary the eccentricity of the disk whereby to regulate the length of the path of movement of the member.

5. In a mechanical movement, the combination of a support, a member mounted to slide on said support and provided with a seat, and a circular disk mounted to rotate on an eccentric axis in said seat and arranged to perimetraly engage the wall of said seat, said seat being of oblong contour with its longer axis disposed transversely to the path of movement of the member and being substantially equal to the diameter of the disk plus the distance between the axis of the disk's rotation and the true center of the disk and having arcuate ends described on a radius substantially equal to the radius of the disk.

6. In a mechanical movement, the combination of a support, a member mounted to slide on said support and provided with a seat, and a circular disk mounted to rotate on an eccentric axis in said seat and arranged to perimetraly engage the wall of said seat, said seat being of oblong contour with its longer axis disposed transversely to the path of movement of the member and being substantially equal to the diameter of the disk plus the distance between the axis of the disk's rotation and the true center of the disk and having arcuate ends described on a radius substantially equal to the radius of the disk, the axis of rotation of the disk being positioned so that when the radius of the disk's eccentricity is substantially parallel with the path of the member the disk nests in one end of the seat.

7. In a mechanical movement, the combination of a support, a member mounted to slide on said support and provided with a seat, and a circular disk mounted to rotate on an eccentric axis in said seat and arranged to perimetraly engage the wall of said seat, said seat being of oblong contour with its longer axis disposed transversely to the path of movement of the member and being substantially equal to the diameter of the disk plus the distance between the axis of the disk's rotation and the true center of the disk and having arcuate ends described on a radius substantially equal to the radius of the disk, the axis of rotation of the disk being so positioned that as the disk completes a movement of substantially one hundred and eighty degrees the disk nests in the end of the seat, locking the member against further movement in the same direction and locking the member against return movement except by rotation of the disk in the proper direction.

8. In a mechanical movement, the combination of a support, a member mounted to slide on said support and provided with a seat, a circular disk mounted to rotate in said seat on an eccentric axis and arranged to perimetraly engage the wall of the seat, said seat being of ob-

long contour with its longer axis disposed transversely to the path of movement of the member and being substantially equal to the diameter of the disk plus the maximum distance between the 5 axis of the disk's rotation and the true center of the disk and having arcuate ends which are described on a radius substantially equal to the radius of the disk, and means for varying the eccentricity of the disk to regulate the length of 10 the path of movement of the member.

9. In a mechanical movement, the combination of a support, a member mounted to slide on said support and provided with a seat, a circular disk mounted to rotate on an eccentric axis in said 15 seat and arranged to perimetricaly engage the wall of the seat, said seat being of oblong contour with its longer axis disposed transversely to the path of movement of the member and being substantially equal to the diameter of the 20 disk plus the maximum distance between the center disk's rotation and the true center of the disk, and having arcuate ends which are described on a radius substantially equal to the radius of the disk, the axis of rotation of the 25 disk being so positioned that as the disk completes a movement of substantially one hundred and eighty degrees the disk nests in the end of the seat, locking the member against further movement in the same direction and locking the 30 member against return movement except by rotation of the disk in the proper direction, and means for varying the eccentricity of the disk to regulate the length of the path of movement of the member.

35 10. In a mechanical movement, the combination of a support, a member mounted to slide on said support and provided with an oblong seat disposed transversely to the path of movement of the member, a circular disk arranged to rotate on an eccentric axis in said seat in engagement with the wall of the seat and to nest in an end of the seat at the completion of a movement of the member, said disk being provided with a 40 radially disposed elongated opening, a post rising from the support, a bearing member rotatable on said post and engaging said opening, and means for adjusting the bearing member along said opening to vary the eccentricity of the disk.

50

55

60

65

70

75

11. In a mechanical movement, the combination of a support, a member mounted to slide on said support and provided with an oblong seat disposed transversely to the path of movement of the member, a circular disk arranged to rotate on an eccentric axis in said seat in engagement with the wall of the seat and to nest in an end of the seat at the completion of a movement of the member, said disk being provided with a radially disposed elongated opening, a post rising from the support, a bearing member rotatable on said post and engaging said opening, and means comprising a rotatable screw bolt mounted on said disk and engaging a threaded hole in the bearing member to vary the eccentricity of said disk.

80 12. In a mechanical movement, the combination of a support, a member mounted to slide on said support and provided with an oblong seat disposed transversely to the path of movement of the member, a circular disk arranged to rotate on an eccentric axis in said seat in engagement with the wall of the seat and to nest in an end of the seat at the completion of a movement of the member, said disk being provided with a radially 85 disposed elongated opening, a post rising from the support, a bearing member rotatable on said post and engaging said opening, and means comprising a rotatable screw bolt mounted on said disk and engaging a threaded hole in the bearing member to vary the eccentricity of said disk.

90 13. In a mechanical movement, the combination of a support, a member mounted to slide on said support and provided with a transversely disposed seat having an end provided with converging arcuate walls, a circular disk rotatably mounted on said support and engaging said seat whereby to reciprocate said member, said disk being mounted on an eccentric axis and said axis 100 being so placed relative to said seat that at the end of a rotary movement of substantially 105 degrees the disk nests in the arcuate end of the seat and thereby is locked against further rotary movement in the same direction.
